UNITED STATES PATENT OFFICE

LYNN JOHNSTON, OF CINCINNATI, OHIO, ASSIGNOR TO THE ELECTRIC RAILWAY EQUIPMENT COMPANY, OF CINCINNATI, OHIO, A CORPORATION OF OHIO

REMOVABLE EXPANSION BOLT

Application filed March 7, 1927. Serial No. 173,312.

This invention relates to expansion bolts such as are adaptable to use for mounting threaded studs in the ceilings of mine passages and the like for receiving trolley hang-
5 ers.

An object of the invention is to provide a device of this kind which is novel and economical in that it may be removed and used again if desired.

10 Another object is to provide such removable feature for an expansion bolt structure without necessitating additional expense in extra parts or additional labor.

These and other objects are attained by 15 the means described herein and disclosed in the accompanying drawings, in which:

Fig. 1 is an elevational view of an expansion bolt of the invention, having a hanger mounted thereon, part being broken away.

20 Fig. 2 is a view taken on line 2-2 of Fig. 1.

Fig. 3 is a cross sectional view of a section of mine roof having a bolt of the invention mounted therein and having associated therewith 25 a tool which may be employed for removing the expansion bolt from its mounting in a ceiling structure.

In the present form of the invention there is employed a sleeve or shell 5, having coarse 30 helical external ridges 6 extending from the top end 7 for a distance along said shell. The shell 5 has a plurality of slots 8 extending longitudinally from the end 7 whereby to provide sections 9 which may be spread 35 apart by means of a tapered conical expander plug 10 which has one or more external ribs 11 which enter slots 8 in the shell to preclude relative rotatory movement of said plug and shell. The plug 10 has a central threaded

40 bore 12 for the reception of a threaded stud 13, which extends through the shell and has its end 14 protruding for a distance from the bottom end 15 of the shell and is adapted to receive the threaded top portion 17 of a hanger 18. If desired, a nut may be interposed between the bottom 15 of the shell and the top 17 of the hanger.

45 Upon tightening the threaded portion 17 of the hanger upon the protruding end 14 of the stud, such hanger portion will abut the

bottom edge 15 of shell 5 whereupon further rotation will turn the stud 13 which will draw the expander plug 10 downwardly between the sections 9 and spread such sections. If the sleeve 5 has been slidably seated and 55 slightly countersunk into a bore in a mine roof or other ceiling structure, the expansion of the sections 9 will wedge the ridged outer walls thereof tightly into the side wall of such hole and secure the structure in place in 60 a manner well known to those skilled in the art. The simultaneous mounting of the stud 13 and expanding of the shell 5 affords a great saving of time and labor in installing hanger mountings. The bearing flange 16 of hanger 65 18 is bound in abutment with the surface of the ceiling thereby resisting transverse strains.

Heretofore expansion bolts have been so difficult to remove without destroying the 70 structure wherein they were mounted that they were invariably allowed to remain in a structure when the location was abandoned. An expansion bolt improperly placed was 75 considered as wasted.

In the present invention the hanger may be removed and the expansion bolt will remain fixed in the structure if this is desired. In order to permit recovery of the bolt from 80 its firm seat in the structure there are provided two or more notches 19 which extend upwardly from the bottom edge 15 of shell 5.

With the hanger 18 removed, a suitable face spanner tool, for example as shown in Fig. 3 may be used. The tool 20 may have a bore or socket 21 of sufficient diameter to receive the protruding end 14 of stud 13 and has a suitable number of projecting lugs 22 which may seat snugly in the notches 19 in 85 bottom of sleeve 6.

Rotary movement of the tool 20 will turn the sleeve 5 which will then function somewhat like a thread cutting tap upon the walls of the bore in which it is secured. Such bores 95 are usually of such depth as to receive the entire shell and the plug 10 loosely entered in the end thereof. The shell may be worked with a tool, such as 20 until it has cut a complete thread in the bore in a mine roof or the 100

like thereby permitting recovery of the entire expansion bolt for re-use elsewhere.

The formation of the ridges 6 in interrupted helical fashion, renders it easy to use a tool 20 with ample leverage to quickly reclaim expansion bolts which would otherwise be lost. Since the sections 9 are spread at the top of the shell, said shell has the desired taper or clearance for efficiently cutting its way out of the mine roof.

It is not intended to limit the invention to the exact structure shown as that may be varied to accommodate the device to other kindred uses all within the scope of the appended claims.

What is claimed is:

1. In a device of the class described the combination with a substance having a bore extending therein, a coarsely and externally threaded and longitudinally slotted expandible shell disposed bodily within the bore and having its proximate end spaced from the surface of the substance, the threads on the expandible shell being of low pitch and shallow depth an expander movable longitudinally in the slotted portion of the shell for expanding said shell and moving the externally threaded portion into binding relation with the wall of the bore in said substance, a bolt receivable in the expander and adapted to be disposed wholly within the bore, and a means comprising a flange for abutment with the surface of the substance and a threaded socket adapted to extend into the bore in the substance and to threadedly receive the end of the bolt, said sleeve first moving into end to end abutment with the expandible shell, rotation of said means serving to actuate the bolt for expanding the shell and for rigidly binding said flange against the surface of said substance, the proximate end of the shell being adapted for the reception of a tool when the flanged means is removed whereby the countersunk shell may be rotated to cause the external threads to cut from the wall of the bore a way to permit removal of the countersunk shell in its expanded position.

2. In a construction of the class described the combination with a substance having a bore of indefinite length therein, of a slotted tubular expandible shell for insertion wholly within the bore beyond the outer end thereof, said shell having external interrupted thread-like members of low pitch and shallow depth, an internally threaded expander disposed in the remote end of the shell for expanding the shell to move the externally threaded portion into binding relation with the wall of the bore, said expander being wholly free of contact with the side wall and end wall of the bore, a bolt receivable in the threaded bore in the expander and a flanged threaded member adapted to be received on the bolt and screwed thereon to engage its flange in abutment with the surface

of the substance, the proximate end of the shell being notched to receive an engaging tool when the flanged means is removed for rotating said shell in expanded condition whereby the external threads may cut a retracting thread into the wall of a substance and permitting removal of the shell.

3. In a construction of the class described the combination with a substance having an unthreaded straight cylindrical bore therein of a longitudinally slotted tubular shell disposed in said bore intermediate its ends and spaced from the surface of said substance, coarse external threads of low pitch and shallow depth on the expandible shell interrupted by the slots, a hanger comprising a flange for abutment with the surface of the substance and a shank for entry into the bore for abutment with the end of the shell, an expander and actuating bolt for threaded entry into the shank whereby the hanger is first secured on the bolt for moving the shank into abutment with the shell and the flange into abutment with the surface surrounding the bore whereby to position the shell in the bore, further rotation of the hanger serving to expand the shell for fixing it into position in the bore, the shell being notched whereby, upon removal of the hanger a tool may be entered in the bore for rotating the shell to effect the cutting of threads by the expanded shell for removing the shell from the bore in expanded condition.

In testimony whereof, I have hereunto subscribed my name this 24th day of February, 1927.

LYNN JOHNSTON.
